(57) CLAIM

The ornamental design for a two-handle cup, as shown and described.

DESCRIPTION

FIG. 1 illustrates a perspective front view of a two-handle cup, which may also be labeled a two-handle sippy cup, of the claimed design;

FIG. 2 is a front view of the two-handle cup shown in FIG. 1;
FIG. 3 is back view of the two-handle cup shown in FIG. 1;
FIG. 4 is a right side view of the two-handle cup shown in FIG. 1;

FIG. 5 is a left side view of the two-handle cup shown in FIG. 1;

FIG. 6 is a top view of the two-handle cup shown in FIG. 1;
and,

FIG. 7 is a bottom view of the two-handle cup shown in FIG. 1.

The broken line showing of a cap or top portion of a two-handle cup in all views forms no part of the claimed design.
